UNITED STATES PATENT OFFICE.

LEO SIMMONS, OF WASHINGTON, DISTRICT OF COLUMBIA.

FLUSHING APPARATUS.

Application filed December 22, 1924. Serial No. 757,435.

To all whom it may concern:

Be it known that I, LEO SIMMONS, a citizen of the United States of America, and a resident of Washington, District of Columbia, have invented certain new and useful Improvements in and Relating to Flushing Apparatus, of which the following is a specification.

This invention relates to improvements in flushing apparatus; and the nature and objects of the invention will be readily understood by those skilled in the art in the light of the following explanations of the accompanying drawings that illustrate what I now believe to be the preferred mechanical expressions or embodiments of my invention from among other forms, constructions and arrangements within the spirit and scope thereof.

An object of the invention is to provide improvements in combinations, constructions, and arrangements with the end in view of producing an exceedingly desirable and improved apparatus or so-called valve.

With this and other objects in view my invention consists in certain novel features, combinations and constructions as more fully and particularly explained and specified hereinafter.

Referring to the accompanying drawings forming part hereof:—

Fig. 1 is a side elevation looking toward the flushing water outlet, the flushing water outlet connection being shown in vertical section.

Fig. 2 is a side elevation looking toward the pressure water inlet, the inlet connection being shown in vertical section.

Fig. 3 is a central vertical section, the valves being shown in normal closed positions and operative parts in normal positions.

Fig. 4 is a detail detached elevation of the dash pot cup.

Fig. 5 is a detail cross section on the line 5—5, Fig. 3.

Fig. 6 is a detached elevation of the finished surface decorative cover cap.

Fig. 7 is a detail elevation of the operating cam.

Fig. 8 is a detached elevation of the top end head or closure providing an unfinished surface and wrench faces.

Fig. 9 is a top plan, the finished surface cover cap and its retaining nut not being

shown, dotted and full lines indicating various positions of the operating handle.

Fig. 10 is a cross section on the line 10—10, Fig. 3.

Fig. 11 is a detail bottom face end view 60 of the operating cam of Fig. 7.

Fig. 12 is a detail perspective of the rotary outlet controlling valve of the dash pot.

Fig. 13 is a section on the line 13—13, Fig. 3, on an enlarged scale. 65

In the particular example illustrated for purposes of explanation, an elongated usually vertical casing is provided consisting of several longitudinal aligned hollow or tubular sections usually detachably united 70 or coupled together through the medium of water-tight screw threaded couplings or connections. For instance, the casing can be composed of a top end tubular section 1, an intermediate section 2, and a lower end section 3, although I do not wish to so limit all features of my invention. 75

In this particular example, the top section 1 provides a chamber for the pressure or service water and a flushing water outlet 80 or port through which the flushing water enters the section 2. The section 2 provides a flushing water chamber or passage having a flushing water outlet for connection to the toilet to be flushed. The section 3 carries 85 the dash pot and provides a water well open to the flushing water passage of section 2.

The tubular section 1 is normally closed at the upper end by a water tight removable top closure, and at its lower end provides 90 a flushing water outlet duct or port 1^a, longitudinally aligned with the casing sections and discharging into the upper end of section 2. The lower end of section 1 provides an annular upwardly facing ledge 95 surrounding said outlet 1^a, and forming a seat or support for the usually flexible annular heavy packing washer 4. The flushing water port or discharge through this washer is normally closed by main flushing 100 valve 5, and auxiliary or pressure relief valve 6, as more fully set forth hereinafter.

In this example, the top section 1 is formed, between its upper and lower ends, with a lateral or side service or pressure water inlet 1^b, formed for coupling to any suitable service or other pressure water supply pipe or connection 7.

The otherwise open upper end of section 1, is normally closed by a removable end 110

pressure-water closure cap 8, having a depending internally threaded flange 8^a that surrounds and screws over the externally threaded upper end of section 1. This closure is usually provided with an internal packing washer 9 to form a tight joint. The closure cap 8, is formed with a fixed central vertical upstanding post or spindle 8^b, closed against passage of liquid from the 10 interior of the casing to the exterior of the closure, and the closure is formed with a vertical guide bore 8^c, longitudinally of said post and open at its lower end into the casing. This guide bore loosely and slidably 15 receives the upstanding longitudinal guide stem 6^a rigid with relief valve 6. The post 8^b is exteriorly formed to provide the closure with rigid nut or wrench receiving faces 8^d, the exterior portion of the post 20 above nut 8^d; being reduced and screw threaded, to provide ledge or shoulder 8^e on the nut.

The upper side of the approximately flat top of the closure, is also preferably formed 25 with an annular ledge or shoulder 8^f adjacent to the junction of the depending flange 8^a, with said flat top. These shoulders or seats 8^e, 8^f, are designed to receive the top and lower edge, respectively, of a removable 30 cup-like perforated cover cap 10, confined to the closure by any suitable means, such as cap nut 11, for instance. The approximately flat top wall of the cap 10 is formed to rest on the shoulder 8^e, and is perforated 35 for the passage of threaded post 8^b. The lower edge of the depending annular wall of cap 10, is formed to fit and be centered by the seat 8^f. The clamp nut 11, is formed to cover the projecting post 8^b, and removably 40 screw thereon down onto the cover cap. The exposed surfaces of the nut 11, cover cap 10, and end closure 8, are nickel plated or otherwise polished and finished, to comply with present trade conditions with respect to bath 45 room and like plumbing fixtures.

Access to the flushing valves 5, 6, the washers, and certain other interior parts of the apparatus, is gained by unscrewing and removal of the pressure cap 8. The wrenches 50 usually employed by plumbers and mechanics seriously damage and mar the exposed ornamental plated or finished polished surfaces of plumbing fixtures to which such wrenches must be applied. I hence provide 55 the readily removable ornamental exteriorly finished perforated slip cover cap 10, that must first be lifted from the casing, before the pressure cap 8, can be reached for removal, and that normally covers and conceals those surfaces of the pressure cap that must be engaged by the wrench during the 60 operation of removing the pressure cap. The surfaces of the pressure cap covered or concealed by the perforated cap, can hence be left unfinished and not in condition to be

so easily damaged or marred as when plated or otherwise finished. The clamp nut 11 is designed for easy unscrewing by the use of a small tool, so that the perforated cover cap can be slipped or lifted by hand from the 70 post 8^d, and the top of the pressure cap 8, and as readily reapplied. When in normal position, the exposed surfaces of the pressure cap, cover cap and clamping nut 11, provide a compact apparently one piece finish at the 75 upper end of the casing. The perforations 10^a in the cover cap are intended to be clearly visible to the plumber or mechanic for the purpose of indicating the presence of a mere 80 finishing cover that does not enclose a water space or chamber and that must be removed to gain access to the pressure cap, intending to warn the plumber or mechanic against applying a heavy rough tool such as a pipe wrench, to the cover cap.

In the specific example illustrated, the washer 4, is clamped against its supporting ledge by metal ring 12, and this ring is held down on the outer edge portion of the washer by spaced upstanding vertical arms 12^a, rigid with the ring, and the spider-like frame consisting of said ring and arms, is held down by ring nut 13, screwing into the internally threaded upper end of casing section 1. The frame consisting of the ring and arms is removable and slidable longitudinally along the cylindrical inner surface of the section 1, and is held against rotation therein by longitudinal rib on the outer surface of the upper end of one of said arms slidable vertically in a vertical longitudinal groove in the inner surface of the upper end of the section 1.

On removal of the end closure the ring nut can be adjusted to tighten or loosen the washer, and on removal of the nut, the ring and its arms can be removed to permit removal of the washer. The arms do not obstruct the service water inlet and do not interfere with or obstruct the flushing valves or the cooperation of the washer 4 therewith.

The lower end of section 1 longitudinally telescopes with the upper end of section 2 and said section ends are joined together for longitudinal removal by longitudinal intermeshing screw threading, and the same is true of the meeting longitudinally telescoping lower end of section 2 and upper end of section 3.

In the example shown, the flushing and relief valves are of the lift type and seat by gravity and water pressure. The main valve 5, is usually of metal, conical in shape, and fits and depends within the washer 4, and is formed with a central vertical pressure relief duct 5^a, leading from the water pressure chamber in section 1, to the flushing water chamber or passage in section 2. This relief passage is normally closed by the coni-

cal relief valve 6, usually integral with guide stem 6^a, in section 1 and depending lift stem section 14 in section 2. The main valve 5 is formed with a top recess and internal annular ledge. Annular washer 5^b, is arranged in said recess on said shoulder and the valve 6 normally seats on the washer and extends down into the central opening thereof. The washer 5^b is removable and is normally clamped to its supporting shoulder by removable ring 5^c, screwing down into the recess in valve 5, and formed with an open-work upwardly extending spider-like frame 5^d, projecting above the relief valve 6, and spaced upwardly therefrom in position to be engaged by the upper end of the relief valve when that valve has completed its upward movement relative to the valve 5 and instituted the pressure relief flow of water through duct 5^a, of valve 5. Continued upward movement of valve 6, then lifts the valve 5, and the two valves then continue their upward strokes together, and the valve 5 remains loosely suspended from the upper end of valve 6, while valve 5, remains above its seat. The lifting or stop frame 5^d, is normally spaced from valve 6 and is always open to water flow therethrough, and the main valve 5 is hence loosely hung by said frame and is free for lateral swing or movement with respect to valve 6 to permit relative lateral freedom and proper centering and seating on its washer. The casing section 2, intermediate its ends, is formed with lateral or radial flushing water outlet 2^a, formed to receive flushing water pipe or other connection 15, for attachment to the toilet or other device or apparatus to be flushed.

40. The otherwise open lower end of section 2, is closed by the section 3, the upper end of which is removably united to the lower end of section 2 by a screw threaded connection.

45. The well section 3 is hollow, closed at its lower end, and open at its upper end to the flushing water chamber or passage of section 2, and its annular vertical wall and lower end are closed against passage of water therethrough.

50. A vertically elongated open-upper end dash pot cup 16, is carried by and arranged longitudinally of and within section 3 in normally fixed relation thereto. This cup is of reduced external cross sectional dimensions throughout its length with respect to the internal dimensions of section 3, to provide a water well 17, within section 3 surrounding the vertical wall of cup 16 and between the lower ends of the cup and section 3, with said water well open at its upper end to the flushing water chamber of section 2. This cup is mounted in an elevated position in the section 3, in the particular example illustrated, through the medium,

55. of a tubular nipple 16^a, forming a reduced central longitudinal rigid extension of the cup and depending from the otherwise closed floor or end wall thereof. The longitudinal bore of this rigid extension nipple 70 extends completely through the nipple and at its upper end opens into the cup through the floor thereof.

60. The bottom end wall of section 3, is formed with a central vertical longitudinal 75 screw-threaded bore therethrough. The cup is secured to and in section 3, by inserting the cup longitudinally into the section through the open upper end of the section, and screwing the nipple 16^a, into said bottom bore of the section, preferably, until the flange or annular shoulder 16^b, of the nipple tightly abuts the top face of the floor of section 3. The lower end of the cup is held elevated above the floor of section 3 by the non-threaded base or upper length of nipple 16^a, between shoulder 16^b, and the cup floor or end, located in the water well 17 of section 3.

65. This base portion is exteriorly and tangentially reduced in thickness at one side or formed with tangential flat side face 16^c. A V-groove 16^d, extends longitudinally of this flat face and tangentially with respect to the nipple bore, and this groove is of such depth that, about midway the length of the groove, it opens through the wall of the nipple into the nipple bore, in the form of a narrow horizontally or transversely elongated slit-like outlet or relief port *a*, tangentially of the cylindrical nipple bore. This slit constitutes a port communication from the lower end of the cup interior through said bore to the lower end of the water well 17.

70. This slit port *a* is closed and opened and its area or capacity is controlled by, a rotary plug valve 18 in the form of a cylinder having a tangential flat portion 18^a, extending through its upper or inner end. This plug 18 extends longitudinally through the bore of the dash pot cup nipple and closes the same against water flow therethrough and leakage to the exterior from the lower or outer end of the bore. The plug extends to and depends at the exterior of the section 3 and is formed with exterior finger head 18^b readily accessible to the fingers for rotation of the plug to set the same at the required position to control the port *a*, to gain the desired flushing action.

75. The lower lengths of the bore of nipple 16^a, and of plug 18, are formed with complementary longitudinal intermeshing screw threaded portions forming packing against water leakage, enabling the plug to be removed, and rendering it possible to screw the plug inwardly to a safe point to prevent leakage so that it may then be rotated to adjust the passage and gauge the length of 130

time in which the valves 5 and 6 are to remain open and thus regulate the required flush of water. The upper or inner cylindrical portion, excepting the flattened part 18^a, 5 of the plug fits the cylindrical inner surface of the nipple bore with a running fit so that the slit port *a*, will be operatively closed by the cylindrical surface of the plug, when the plug is turned or rotated to a position with 10 the flat face 18^a, remote from the V-shaped slit port *a*. The flattened portion of the plug forms a longitudinal water passage, within the nipple, that is open at its upper end into the dash pot cup and is otherwise closed against liquid escape or leakage, except when the flat portion 18^a, is opposite slit port *a*, so that the portion of the nipple wall containing said slit forms a portion of the wall of said longitudinal water passage. 15 When the plug is in this just mentioned position, fluid flow to and from the cup is established through said slit port and the nipple. By slightly rotating the plug, the slit port *a*, can be closed, or can be opened 20 throughout its length, or can be fractionally opened to the extent required by the desired quantity of water to be discharged at each flushing operation.

The stem that controls the main and relief 30 valves 5, 6, is provided at its lower end with a piston 19 vertically movable in the dash pot cup 16, and this piston and the cup are relatively formed and constructed to cause inflow of flushing water into the cup under 35 the piston on the opening movements of the main and relief valves, i. e. on the upward movement of the piston so that the cup will be full of water before the piston starts on its downward movement. The upward 40 movement of the piston also exerts suction pull through the slit port *a*, to draw water through said port and the nipple into the bottom of the cup. The piston and cup are also relatively formed to reduce to the minimum 45 water leakage or pressure relief from the cup during the downward movement of the piston, except through the slit port *a*.

It will be observed that the V or flaring 50 form of the port *a*, provides sharp or feather edges forming the longitudinal walls of the port, whereby the inrush and outrush of water during the ascent and descent of the piston, will readily free the port from sediment or other foreign matter tending to clog 55 or choke the same. These feather edges tend to prevent sediment and the like from collecting in and choking the port.

Various constructions can be provided for 60 causing quick filling of the cup, although I show the piston provided with a flexible cup washer 19^a, having a depending annular flexible skirt formed to contract for water passage on the upward stroke of the piston and to expand against the inner surface of 65 the cup and against upward passage of water

on the downward movement of the piston. Also, if so desired, the internal diameter of the cup can be enlarged at the upper end of the cup to aid in such rapid filling of the cup with water under the piston. Also, some 70 inflow of water to the cup through port *a*, from the water well, will take place during the upward stroke of the piston, while the speed of the descent of the piston and parts then carried thereby will be controlled by 75 the outflow through and consequently by the area or capacity of the port *a*, which can be most accurately and readily varied or adjusted by plug 18. The valve stem 14 forms a stiff valve lifting and controlling 80 rod-like member from the piston to the valves, and in the example shown is composed of two longitudinal alined sections removably united by longitudinal screw thread joint 14^a, for purposes of assembly 85 and taking down, and if need be, to permit longitudinal shortening or extension of the lift stem.

Various means can be employed, operative 90 from the exterior of the casing, for lifting the stem with the dash pot piston and the relief and main flushing valves to initiate the flushing flow, and for then releasing the stem so that the dash pot and piston can 95 control the descent of the valves and the length of time of the flushing water flow.

However, I show improved and peculiarly 100 advantageous means for this purpose. In the particular example illustrated, the casing section 2, is cast or otherwise formed at a point remote from outlet 2^a, with a hollow lateral bulge or offset 2^c, forming a lateral or side recess or chamber opening into the flushing water chamber of the section and otherwise closed against water outflow to the 105 casing exterior. A vertically-swingable horizontally-disposed lifting member or lever 20, is fulcrumed in said bulge on transverse axis 21, and is arranged in the bulge and extends therefrom transversely across section 2, past the lifting stem 14 although I do not wish to so limit all features of my invention.

The shaft pivot pin or axis 21, extends 110 transversely across the bulge or offset 2^c, and is supported by the opposite vertical walls thereof, and, in the example shown, the outer end of the lever member 20, is formed with a transverse hub receiving and rotatable on the axis 21.

The lever member 20, is operatively connected with the lift stem 14 in any suitable manner or by any suitable means, to operate said stem to lift the flushing valves (main valve 5, and relief valve 6) to start the flushing operation. For instance, I show the free end of the lever member loosely crossing the lower section of stem 14, under a lifting shoulder 14^b, of the stem in such manner that when the lever member is rocked to elevate its 120 125 130

free end, such end will strike said shoulder and through the medium thereof elevate the stem to lift the flushing valves. If so desired, the free end of the lever member can be longitudinally forked or bifurcated and thus loosely straddles the lifting stem below corresponding lateral downwardly-facing lifting shoulders 14^b , formed on opposite sides of the stem, and above upwardly-facing lateral shoulders 14^c , correspondingly arranged on opposite sides of the stem. If so desired, these shoulders 14^b , 14^c , can be of the approximate knife-edge type, and the stem can be flattened or reduced in thickness at its opposite sides between lifting shoulders 14^b , and depressing shoulders 14^c , although I do not wish to limit all features of my invention to such connection between the lever member and the stem nor to the bifurcated and twin shoulder arrangement.

Suitable means are provided to operate the lever member to lift the flushing valves (first the relief valve, and then the main valve through the medium of the relief valve) to start the flushing operation by lifting engagement of the member with shoulders 14^b , and to then release said member, permitting its free end to drop to and rest on the stop or depressing shoulders 14^c .

In the example illustrated I show a thrust cam as means of actuating the lever member on its valve-lifting stroke, and then to permit the valve to close under action of gravity and the flushing water flow or pressure, while the speed of valve closing movement is controlled by the dash pot device. Such lever member operating means, in this example is mounted in and carried by the casing bulge or offset 2^c , and embodies a vertical oscillatory spindle or shaft 22, extending from a point at the exterior of the casing to a point within the same, and extending through the top wall of the offset 2^c , and carried by and rotatable in a suitable preferably removable plug in said wall forming a journal or bearing box for said spindle. At its upper end, at the exterior of the casing, said spindle is equipped with a lateral operating handle 23, normally fixed thereto. In the upper part of the chamber within the casing offset 2^c , the lower end of the spindle is formed with or carries a disk 24 fixed thereto and arranged centrally above the fulcrum of the lever member 20. The upper end or side of this disk provides an annular shoulder bearing against the top wall or closure of the casing offset to receive the upward thrust of the cam disk in action and limit upward movement of the spindle 22.

The fulcrum hub of the lever member 20, is provided with a fixed stud or pin 20^b , projecting upwardly and outwardly therefrom at an angle, and a grooved roller 20^e , is mounted to revolve on said pin.

The disk 24 is formed with a depending

rounded thrust cam and trip nose or toe arranged a distance radially from the longitudinal axis of the disk 24 and its spindle and hence eccentric with respect thereto and designed to engage and gradually depress the roller 20^e and consequently swing the lever member on its valve lifting stroke, as the handle 23 is swung on an operative stroke, and to slip past said roller and free the lever member before said handle completes such stroke. This nose or toe is double to thus act on and slip past the roller, on each operative swing of the handle, i. e. when the handle is swung forward and when the handle is swung backward, referring to Fig. 9. This is provided for by limiting the back and forth swing of the handle to an arc prescribed by stops 26 (Fig. 13) projecting inwardly from the vertical wall of the casing offset 2^c , and cooperating with stop shoulders or a radial lug 24^d , rigid with the disk. In this instance, the stop 24 d is arranged at the outer side of and is centrally arranged with respect to the depending oppositely curved portions of the working or operative edge 24^b , of said depending toe or nose. The disk is formed with a depending edge track arranged above the roller 20^e , and this track embodies the elevated end portions 24^a , approximately concentric with the axis of the disk that gradually curve downwardly and converge to form the working edge 24^b of the said nose or toe having a curved crown or tip to slip past the roller in either direction. The working edge 24^b , is formed to ride on the grooved roller 20^e and depress the same the maximum distance, say when the handle 23, reaches a position about midway its stroke, see middle position shown by dotted lines Fig. 9, and the flushing water will continue to flow as the flushing valves are held elevated so long as the operator holds the handle in this middle position. However, if the operator does not hold the handle in this position, the curved cam nose will slip past the roller, thereby freeing the lever member after the flushing valves have been lifted their full upward stroke permitting said member to drop by gravity onto the shoulders 14^c leaving the member and the valves then entirely free and independent of the handle 23 and the thrust trip means.

The cam arrangement attains a powerful leverage action, by the application of but slight force to handle 23, to depress the short arm of the lever the short distance necessary to the relatively long full lift of the flushing valves through the long upward stroke of the long arm of the lever member, and the parts can be moved to cause a flushing operation by swinging the handle in either direction from either stop 26 toward the other stop 26.

The constructions disclosed by my Patents No. 1,531,514 dated March 31, 1925, and No. 1,534,877 dated April 21, 1925, are not herein claimed apart from the improvements disclosed by the instant case, but I do not desire to limit said improvements to use in connection with said constructions.

It is evident that various changes, modifications, and variations might be resorted to without departing from the spirit and scope of my invention and hence I do not wish to limit myself to the exact disclosures hereof.

What I claim is:

15. 1. Flushing apparatus lift valve operating devices embodying a lever member, and an exterior operating handle having a thrust and trip device for swinging and slipping past said member.
20. 2. Flushing apparatus comprising a casing, flushing lift valve means therein, and operating means for lifting and then releasing said valve means, said operating means embodying an oscillatory spindle extending from the interior to the exterior of the casing and having an exterior handle for oscillating the spindle and within the casing having a thrust cam nose, and means cooperating with and independently of said nose
25. 30. to be operatively moved and then released by said nose on each operative movement of said handle.
35. 3. Flushing apparatus comprising a casing, flushing lift valve means therein, means for lifting said valve means to start a flushing operation, and operating mechanism for said lifting means, embodying a member movable to actuate said lifting means on a valve lifting stroke, and an exterior handle provided with cam trip means within the casing to ride on and move said member on an actuating stroke and then release the same.
40. 45. 4. Flushing apparatus comprising a casing, flushing valve means therein, and means to move said valve means to start a flushing operation, embodying a lever member, and a thrust disconnected from said member and arranged to operatively swing the member and then slip past the same free the member for independent return movement, said thrust provided with manual operating means operative from the exterior of the casing.
55. 60. 5. Flushing apparatus comprising a casing, flushing lift valve means in the casing, a lift stem for said valve means, and means for lifting and then releasing said stem for independent flushing valve closing movement, embodying an exterior operating handle and a double thrust cam nose within the casing oscillatory back and forth by said handle, and stops limiting the oscillations of said nose.
65. 6. Flushing apparatus comprising flush-

ing valve means, a lift stem therefor; dash pot means controlling the closing movement of said means through the medium of said stem, and operating mechanism for lifting the valve means through the medium 70 of said stem and then releasing the same for descent under the control of said dash pot means, said mechanism embodying a motion multiplying lever member, a lever-member swinging thrust and trip cam member 75 swingable back and forth in opposite directions and arranged to operatively swing and release said lever member on each swing of the cam member, and an exterior handle for swinging the cam member.

7. In flushing apparatus, means for lifting and releasing the flushing valve means, comprising a motion multiplying rocking member constantly tending to drop to normal position, a spindle in the valve casing 85 having an exterior handle and an interior cam nose constructed and arranged to ride on and slip past said member to rock the same on a valve lifting stroke and then release the same for free and independent 90 return.

8. Flushing apparatus provided with flushing lift valve means, and operating mechanism for moving said means to start a flushing operation, embodying a lever member mounted in the valve casing having a short lever arm provided with a roller, and a cam nose provided with a swingable support and exterior operating means; said nose swingable back and forth and constructed and arranged to ride on said roller to operating swing the lever member and then slip past the same and free thereof on each back and forth swing to permit free and independent return movement of 100 the lever member.

9. Flushing apparatus provided with flushing lift valve means, and a valve and water casing, said casing having a bulge or offset, and operating mechanism for lifting said valve means, embodying a vertical spindle mounted in said offset and having an exterior handle and within the offset having a disk with a depending cam nose, stops limiting the back and forth swing of the nose, a lever member in the casing and normally free of said nose and constructed and arranged with respect to the nose to be rocked thereby to lift the valve means on each swing of the nose.

10. Flushing apparatus comprising a casing having a lateral bulge or offset, flushing lift valve means, a lift stem therefor, a stem-lifting lever member fulcrumed in and arranged transversely of said casing and loosely traversing said stem, said stem having a lifting stop above and to be engaged by said member, and a spindle mounted in said offset and having an exterior handle and within the offset having an oscillatory 125

rounded thrust cam nose arranged to ride on and swing said member to lift and release the stem on swing of the handle in either direction.

- 5 11. Flushing apparatus embodying a pressure and flushing water casing, lift flushing valve means therein having operating mechanism, a removable end closure for said casing, said closure having an exterior wrench face, a removable perforated cap covering the wrench face portion of said closure and having finished exterior surfaces, and means for removably confining said cap. 70
- 10 12. A flushing apparatus embodying an outer casing having a bottom end section enclosing an interior dash pot or well, open to receive the water passing to the casing and dash-pot or well; means of a stem for lifting a main and relief valve and controlling the closing movements thereof, provided with a dash pot piston; an enclosed dash pot cup or well, for said piston, supported by said outer casing section; said 75 piston arranged to work within the said dash pot water well; having a bottom V-shaped relief passage opening into the bottom of said casing; a plug having operative means at the exterior of said section to regulate and control the capacity of said passage. 80
- 15 13. A flushing apparatus having an outer casing with a bottom end section enclosing a dash pot forming a water well therein, open to form a water passage to the casing and dash-pot; a lift stem to operate a main and relief valve operative in the casing; means at the lower end for controlling the closing movements thereof; the lower end of said 85 lift stem means having a dash pot piston, a dash pot cup or well for said piston supported by said casing section; said well having a bottom relief passage opening into the bottom of said outer casing, and a plug having operative means at the exterior of said 90 casing section for controlling the capacity of said water passage; said passage having a V-shaped edge slit port; a regulating plug having a flat side, and smooth loose-fitting, cylindrical portion, cooperating with said port. 95
- 20 14. A flushing apparatus or device embodying a casing having a bottom end section, forming a water well with a dash pot cup with said well, both open to receive the flow of water to said casing and to permit the water to pass relatively free from the outer casing to the dash pot cup or well by gravity or suction means; a stem for lifting a main and relief valve and controlling the closing movements thereof; said device, at its lower end, provided with a dash pot piston and a dash pot cup being housed or screwed into and supported by 100 said outer casing section; said piston well
- 25 being arranged within the outer water wells and having a dash pot cup, a bottom relief passage opening from the bottom of the inner dash pot cup or well into the bottom of said outer well or casing; a regulating screw plug as operative means at the bottom end and exterior of said section for controlling the capacity of said water passage; said passage being a V-shaped slit port; a screw plug having a flat side and a loose-fitting smooth, cylindrical portion, at the upper end, and cooperating with said port; said dash pot cup or well having a dependable nipple with a relatively longitudinal bore opening from the outer and lower end 105 through the floor of the casing and cup and receiving said screw plug, the same being accessible from the outer bottom of said casing and passing a V-shaped slit port in the neck above the screw-threaded portion of said nipple. 110
- 30 15. Flushing apparatus embodying a casing, flushing valve means, means controlling the flushing valve closing movement and the flushing operation, and a manually-operated trip and thrust cam member constructed and arranged to actuate the valve means on its opening movement and then trip and free the same for closing movement independent of said member. 115
- 35 16. Flushing apparatus embodying a casing, flushing valve means, means controlling the flushing valve closing movement and the flushing operation, and a manually-operated oscillatory spindle provided with an eccentric trip and thrust cam nose swingable back and forth between limiting stops and constructed and arranged, on each swinging movement, to actuate the valve means on its opening movement and then free the same 120 for independent closing movement. 125
- 40 17. Flushing apparatus or device having a casing with a cylindrical bore, a V-shaped notch providing a slit port into said bore, sharp edge walls, and a rotary regulating screw plug having a cylindrical portion relatively closing said bore except for the reduced side and loose-fitting smooth portion, providing a liquid passage leading to said port, whereby the port can be relatively 130 closed or opened and varied in capacity by partial rotation of the said regulating plug. 135
- 45 18. Flushing apparatus having a casing and a bore with a V-notch casing at the lower end providing a slit port into said bore, and a flattened side, loose-fitting rotary regulating plug in said bore and in connection with an outer and inner casing, said inner casing providing a liquid passage through its neck or lower portion forming 140 a communication with said outer casing regulated by rotation of said plug. 145
- 50 Signed at Washington, D. C., this 22nd day of December, 1924.
